UNITED STATES PATENT OFFICE

136,465

DESIGN FOR A PORTABLE ELECTRIC MOTOR-DRIVEN TOOL UNIT

Wendell K. Beckwith, Whitewater, Wis., assignor
to Milwaukee Electric Tool Corporation, Mil-
waukee, Wis., a corporation of Wisconsin

Application April 18, 1942, Serial No. 106,621

Term of patent 14 years

To all whom it may concern:

Be it known that I, Wendell K. Beckwith, a citizen of the United States, residing at Whitewater, in the county of Walworth and State of Wisconsin, have invented a new, original, and ornamental Design for a Portable Electric Motor-Driven Tool Unit, of which the following is a specification, reference being had to the accompanying drawing, forming part thereof.

In the drawing:

Fig. 1 is an outside side view of a portable electric motor-driven tool unit embodying my new design; and

Fig. 2 is a transverse vertical section through the tool unit of Fig. 1, taken along the line 2—2.

While only one side of the tool is shown in the drawing, the opposite side which is not shown, is substantially like the side actually shown in Fig. 1.

I claim:

The ornamental design for a portable electric motor-driven tool unit, substantially as shown and described.
